UNITED STATES PATENT OFFICE.

FRANK TAFT, OF NEW YORK, N. Y.

DESIGN FOR A BINDER-TAB.

SPECIFICATION forming part of Design No. 33,166, dated September 4, 1900.

Application filed August 9, 1900. Serial No. 26,443. Term of patent 7 years.

To all whom it may concern:

Be it known that I, FRANK TAFT, a citizen of the United States, and a resident of the city of New York, borough of Brooklyn, in the county of Kings and State of New York, have invented and produced a new and original Design for a Binder-Tab, of which the following is a specification, reference being had to the accompanying drawings, forming a part thereof, in which—

Figure 1 is a perspective view of a binder-tab embodying the features of my design, and Fig. 2 is a plan view of the same.

The design consists in a base or body section A and a head B, appearing continuous with the base or body, which head is T-shaped in general outline, and in the head, where the projecting members connect with the

shank, semicircular recesses occur partly in the under edge of said projecting members and in the side edges of the shank of the T-head, imparting a hook-like contour to the projecting members of the head.

Having thus described my invention, I claim as new and desire to secure by Letters Patent—

The design for a binder-tab herein shown and described.

In testimony whereof I have signed my name to this specification in the presence of two subscribing witnesses.

FRANK TAFT.

Witnesses:

J. FRED. ACKER,
EVERARD BOLTON MARSHALL.
